D. S. KENNEDY,
TYPOGRAPHICAL CASTING MACHINE,
APPLICATION FILED AUG. 25, 1921.

1,415,454.

Patented May 9, 1922.

UNITED STATES PATENT OFFICE.

DAVID S. KENNEDY, OF BROOKLYN, NEW YORK, ASSIGNOR TO MERGENTHALER LINOTYPE COMPANY, A CORPORATION OF NEW YORK.

TYPOGRAPHICAL CASTING MACHINE.

1,415,454.

Specification of Letters Patent.

Patented May 9, 1922.

Application filed August 25, 1921. Serial No. 495,272.

To all whom it may concern:

Be it known that I, DAVID S. KENNEDY, a citizen of the United States, residing at Brooklyn, in the county of Kings and State 5 of New York, have invented certain new and useful Improvements in Typographical Casting Machines, of which the following is a specification, reference being had therein to the accompanying drawing.

10 My invention relates to typographical casting machines, such as linotype machines of the general organization represented in U. S. Letters Patent to O. Mergenthaler No. 436,532, wherein a melting pot is arranged 15 to deliver molten metal into a slotted mold and up against a composed line of matrices to produce a type bar or slug bearing on its edge type characters corresponding to the intaglio characters of the matrices. In these 20 machines, the molten metal is ordinarily introduced into the mold by means of a single pump plunger disposed within the pot, but in some instances, as when large slugs are to be cast, two or more such pump plungers 25 are employed, these plungers being operated simultaneously in filling the mold. In the use of a plurality of pump plungers, it is important that all of them be connected to the operating means during the casting 30 operation, not only because the combined action of the plungers is required to charge the mold, but also because the operation of one plunger independently of another might lead to serious consequences. Thus, if one 35 plunger were operated while another is disconnected from the operating means, the pressure exerted on the molten metal by the connected plunger would necessarily react on the disconnected plunger and force the 40 latter, together with a charge of molten metal, from the casting pot. Or, if at the time, the disconnected plunger had been taken from the pot for cleaning or otherwise, a more violent splash of molten metal 45 would naturally result.

The present invention, to guard against such occurrences as the above, is directed to a safety device which will prevent the operation of one pump without the other. 50 The exact form and arrangement of the parts will be best understood from the detailed description to follow:

Referring to the drawings:

Fig. 1 is a vertical section taken 55 through the casting mechanism of a lino-

type machine having my invention embodied therein;

Fig. 2 is a section taken on the line 2—2 of Fig. 1, looking downwardly;

Fig. 3 is a detail view;

Fig. 4 is a section taken on the line 4—4 of Fig. 1, looking forwardly or toward the right in the latter figure.

In Fig. 1, the parts are shown in the relative positions they occupy just prior to the casting operation. In this condition of the parts, the slotted mold A, carried by the rotary disc A¹, is closed at the front by the composed line of matrices X presented momentarily thereto by the first elevator 60 B, and it is closed at the rear by the mouth piece C¹ of the melting pot C sustained within the rocking frame or jacket D. Within the pot C are located the two distinct pump pistons or plungers E fitted 70 into the separate wells or cylinders E¹, both communicating with the throat or passage C² through which the molten metal is forced into the mold during the casting operation. The pump plungers E are provided 80 with the connecting rods or links E², which latter are detachably connected, as by the removable pins E³, to the forked end of the common vertically movable lever F formed at its opposite end with the bearing 85 sleeve F¹ mounted loosely on the fixed transverse rod G of the machine frame. The sleeve F¹ has two arms F² and F³, the former carrying the roller F⁴ which is arranged to track upon the periphery of the ordinary 90 rotary cam F⁵, and the latter being extended laterally beneath the further lever F⁶ which is also mounted loosely on the fixed rod G and which has its free end connected to the tension spring F⁷ pulling downwardly 95 thereon from a fixed part of the machine. The lever F is also urged downwardly by the customary spring-actuated rod F⁸ acting directly thereon. As well understood, the peripheral face of the cam F⁵ is concentric throughout except at one portion of its circumference, where it is cut away or formed with a depression to provide the usual sloping surfaces F⁹ and F¹⁰. When the machine is at rest, the roller F⁴ is in 100 contact with the concentric portion of the cam F⁵, so that the two plungers E are maintained in their raised or inoperative condition, as indicated in Fig. 1. This condition obtains until the casting period ar-

rives, when the cam (rotating in the direction of the arrow) brings its sloping surface F^9 into engagement with the roller F^4 , which then descends along such surface to 5 the bottom of the depression, thus permitting the springs F^7 and F^8 , through the connections described, to depress both plungers simultaneously and force a charge of molten metal into the mold. As the cam continues 10 to rotate, the roller F^4 is engaged sooner or later by the sloping surface F^{10} , and the parts are thereby restored to and maintained in their original condition to await the next 15 casting operation. The foregoing parts and their mode of operation are well known and in themselves constitute no part of my invention.

As before stated, the present invention is directed to a safety device whereby neither 20 pump plunger can be operated independently of the other. To this end, in the embodiment illustrated, the lever F is provided with two independent locking detents H held in place thereon by a trough-shaped plate 25 H^1 . At their rear ends, the detents H are formed with laterally projecting lugs H^2 adapted to cooperate with abutments J formed on the two arms of a bifurcated member J^1 fixed to the machine frame and 30 straddling the lever F . At their forward ends, the detents H are formed with lateral extensions H^3 arranged to be engaged by the plunger rods E^2 , springs H^4 , which pull forwardly thereon, tending constantly to 35 maintain said detents in such engaging relation. According to this arrangement, when both of the rods E^2 are connected to the operating lever F , as in Figs. 1 and 2, the detents H are held in inactive position, that 40 is to say, with their projecting lugs H^2 to the rear and clear of the fixed abutments J , so that the two pump plungers are free to be operated in the manner previously described. On the other hand, when either one 45 of the rods E^2 is disconnected from the operating lever F , as in Fig. 3, the corresponding detent H is moved forwardly to active position by the attached spring H^4 , that is to say, with its projecting lug H^2 located above 50 and in engaging relation with the associated fixed abutment J , thereby locking the lever F against depression during the rotation of the cam F^5 , and consequently preventing the operation of either pump plunger. In this 55 way, the dangers previously alluded to are entirely avoided.

In the accompanying drawings, I have shown my invention merely in preferred form and by way of example, and as applied 60 to a linotype machine of the general class stated, but obviously there are various other embodiments and adaptations which will suggest themselves to those skilled in the art and still be comprised within its spirit. 65 Generally speaking, I desire to be under-

stood but I do not limit myself to any specific form or embodiment except in so far as such limitations are specified in the claims.

Having thus described my invention, what 70 I claim is:

1. In a typographical casting machine, the combination of a melting pot, a plurality of pump plungers located therein, operating means for said plungers, and means for preventing the operation of one plunger independently of another. 75

2. In a typographical casting machine, the combination of a melting pot, a plurality of pump plungers located therein, operating 80 means detachably connected to the respective plungers, and means for preventing the operation of said plungers when one is disconnected from the operating means.

3. In a typographical casting machine, the 85 combination of a melting pot, a plurality of pump plungers located therein, operating means detachably connected to the respective plungers, and locking means to prevent the operation of the plungers, said locking 90 means being inactive when all of the plungers are connected to the operating means and rendered active by the disconnection of any one of the plungers from the operating means. 95

4. In a typographical casting machine, the combination of a melting pot, a plurality of pump plungers located therein, operating means therefor including a common lever 100 detachably connected to the respective plungers, and locking means to prevent the action of said lever when one of the plungers is disconnected therefrom.

5. In a typographical casting machine, the combination of a melting pot, a plurality of 105 pump plungers located therein, operating means therefor including a common lever detachably connected to the respective plungers, and locking means to prevent the action of said lever, the said locking means being 110 inactive when all of the plungers are connected to the operating lever and rendered active by the disconnection of any one of the plungers from the operating lever. 115

6. In a typographical casting machine, the 115 combination of a melting pot, a plurality of pump plungers located therein and provided with connecting rods or links, operating means therefor including a common lever 120 detachably connected to the rods or links of the respective plungers, and independent spring-actuated locking detents carried by said lever and controlled in their action by the plunger rods. 125

7. In a typographical casting machine, the 125 combination of a melting pot, a plurality of pump plungers located therein and provided with connecting rods or links, operating means therefor including a common lever 130 detachably connected to the rods or links of

the respective plungers, independent spring-actuated locking detents carried by the operating lever and arranged in position to be engaged by the plunger rods, and stationary abutments with which the locking detents are adapted to engage when in active position.

8. In a typographical casting machine, the combination of the pot C, the pump plungers 10 E provided with the rods or links E², op-

erating means including the lever F detachably connected to the rods E², as by the removable pins E³, the spring-actuated locking detents H carried by the lever F, and the member J having the abutments J¹ to cooperate with the locking detents. 15

In testimony whereof, I have affixed my signature hereto.

DAVID S. KENNEDY.
